UNITED STATES PATENT OFFICE.

J. RAYMOND PLANK, OF GRAND RAPIDS, MICHIGAN.

DESIGN FOR A RADIOLAERIAL.

Application filed June 14, 1926. Serial No. 18,089. Term of patent 7 years.

To all whom it may concern:

Be it known that I, J. RAYMOND PLANK, a citizen of the United States, residing at the city of Grand Rapids, in the county of Kent and State of Michigan, have invented a new, original, and ornamental Design for Radioaerial, of which the following is a specification, reference being had to the accompanying drawing, forming a part thereof.

Fig. 1 is a perspective view of a radioaerial showing my new design, and Fig. 2 is a plan view of the same.

I claim:

The ornamental design for a radioaerial, as shown.

J. RAYMOND PLANK.
